UNITED STATES PATENT OFFICE.

FREDERICK W. HORN, OF BROOKLYN, ASSIGNOR TO KOCH SONS & CO., OF NEW YORK, N. Y.

DESIGN FOR A NAME-PLATE.

SPECIFICATION forming part of Design No. 16,690, dated May 18, 1886.

Application filed April 5, 1886. Serial No. 197,886. Term of patent 7 years.

To all whom it may concern:

Be it known that I, FREDERICK W. HORN, of Brooklyn, in the county of Kings and State of New York, have invented a Design for a Name-Plate, of which the following is a specification.

Name-plates, especially those placed on album-covers, are often lacking in artistic beauty, and detract from the appearance of the article to which they are connected.

The leading feature of my design is the configuration of the ornamental name-plate.

In the drawings, Figure 1 is a plan view of the name-plate, and Fig. 2 is a section of the same at the line *x x*.

The design of my name-plate consists of a foliated configuration, *a b c*, and a curved stem, *d*, the edges of the plate being beveled, as

shown in Fig. 2, and the outer edges of the leaves indented, and being compound curves in imitation of shamrock-leaves, the entire plate having the artistic appearance as shown.

This design may have either three or four leaves, substantially as represented.

I claim—

The design of the ornamental configuration of the name-plate, consisting of the group of leaflets with compound curved outlines and beveled edges, substantially as described and shown.

Signed by me this 31st day of March, A. D. 1886.

FREDERICK W. HORN.
